UNITED STATES PATENT OFFICE.

WASHINGTON BECK, OF PITTSBURG, PENNSYLVANIA.

DESIGN FOR ORNAMENTING GLASSWARE.

Specification forming part of Design No. 7,755, dated September 15, 1874; application filed July 7, 1874.
[Term of Patent 7 years.]

To all whom it may concern:

Be it known that I, WASHINGTON BECK, of Pittsburgh, in the county of Allegheny and State of Pennsylvania, have invented a new and useful Design for Ornamenting Glassware; and I do hereby declare the following to be a full, clear, and exact description thereof, reference being had to the accompanying drawing, forming a part of this specification, in which—

Figure 1 represents the ornamentation as applied to a sugar-bowl, and Fig. 2 as applied to a cream-pitcher.

A represents the article of glassware to which the ornamentation is applied. Upon a plain surface I make a series of parallel elevations or depressions, of the general configuration shown at $b b' b' b'' b'' b'''$, seven or more in number, either rounded or prismatic in form, the center one, b , of the series being the longest, and those on the sides being in pairs of equal length, but shorter than the pair next toward the center, (for instance, $b' b'$ shorter

than b , $b' b'$ shorter than $b' b'$, and so on,) so that the series have the general outline of a triangle having two equal sides. Upon a raised or sunken band, c , are hemispherical or equivalent-shaped elevations or depressions c' , which, taken together, form a border that may be used in combination with the parallel elevations or depressions $b b' b' b'' b'''$, &c.

What I claim as my invention, and desire to secure by Letters Patent, is—

A design for glassware, composed of the parallel elevations or depressions $b b' b' b'' b'''$, either rounded or prismatic in form, and the border c , having the elevations or depressions c' , substantially in the manner above described.

In testimony whereof I, the said WASHINGTON BECK, have hereunto set my hand.

WASHINGTON BECK.
